UNITED STATES PATENT OFFICE

ASA SEELEY, OF OWOSO, MICHIGAN

GAS-PRODUCING APPARATUS

Application filed July 18, 1925. Serial No. 44,593.

This invention relates to gas making apparatus, and has for an object to provide means for removing deposits from pipes or conduits employed in carrying gas from retorts, and the device may be regarded as an improvement in means for establishing communication between retorts, the gas washer stand-pipe and the waste heat flues.

It is an object of this invention to utilize heat from the retorts, for burning out the retorts and the connection between the retorts and the washer stand-pipe after the gas has been discharged from the retort and while the retort is being recharged; and it is a further object of this invention to provide novel means by which the operators or stokers may interrupt direct communication between the retort and the washer stand-pipe and divert heat which radiates from the retort while it is being drawn and recharged to the connections between the retort and the washer stand-pipe so that the same may be cleared of deposits which, under ordinary conditions, accumulate in the connections and impede the flow of gas from the retort to the washer stand-pipe, the deposits accumulating in the retorts and connections being discharged into the waste heat flues which are usually adjacent to the washer stand-pipes.

With the foregoing and other objects in view, the invention consists in the means for removing deposits from washer stand-pipes and their connections, as hereinafter more fully set forth and claimed.

In describing the invention in detail, reference will be had to the accompanying drawings forming part of this application wherein like characters denote corresponding parts in the several views, and in which—

Figure 1 illustrates a view in elevation of a fragment of a gas producing apparatus with the invention applied thereto;

Figure 2 is a front elevation of a mouth piece used for connecting a retort with a stand-pipe or with a waste heat flue;

Figure 3 is a sectional view taken transversely through one of the valve boxes;

Figure 4 is a sectional view on the line 4—4 of Fig. 3, said view showing a connecting piece which extends from the part attached to a stand-pipe and to the waste heat flue; and

Figure 5 is a side elevation, partly in section, showing the stand-pipe, the waste heat flue, the retort partly in section and associated parts.

The invention forming novel subject-matter of this application is a gas producing apparatus having retorts of usual construction, such retorts extending through the front walls of a furnace, each retort having a mouth piece and a door, both located beyond the front wall of the furnace.

The mouth pieces of each of the retorts are in direct communication with a casing that leads to flues of a chimney, one flue constituting a stand or washer pipe and the other flue a waste heat flue, the casing having associated therewith a damper for establishing communication with either of the flues, the casing being constructed to provide direct communication of the retort with the stand-pipe or flue and also communication with a waste heat flue, especially when the door of the retort is opened. Such construction provides means whereby when the stand-pipe or flue has its opening in communication with the casing closed, at which time the door of the retort may be opened, there will be induced an up-draft in the waste heat flue that carries with it light ash, gas and other light residue which may be drawn by the up-draft into the waste heat flue, thereby preventing such material and heated air being projected outward through the door towards the front of the furnace.

In practice, each vertical bank of retorts is provided with a washer stand-pipe and with a waste heat flue, and a casing between the flues of the chimney and the mouth pieces

of the retorts, the casing being of such construction that its outlet will be opposite the opening through the wall of a stand-pipe, the construction also providing means whereby the cut-off damper or valve is located beyond the usual mouth piece of the retort, whereby said valve and its operating parts are not subjected to the intense heat produced within the retort.

10 In these drawings, 5 and 6 denote conventional forms of seal boxes with which the washer stand-pipes 7 communicate and the washer stand-pipes are provided with the usual connections for a water line 9. The 15 washer stand-pipes or flues have the usual ports or openings such as 10 which communicate with retorts 11 through the mouth pieces 12 and extensions 14 which communicate with a casing or valve box 13.

20 In the present embodiment of the invention, a valve box 13 is provided at each port of the washer stand-pipe.

25 Waste heat flues 15 are parallel with the washer stand-pipes 7, and communicate with the valve boxes or casings 13 with the several ports 10 and 16 with the flue of the washer stand-pipe 7, and the waste flue 15' of the chimney, the flues being contiguous in order that the valve box may be of a minimum size. 30 Each waste heat flue 15 in horizontal alignment with the ports or openings 10 has ports such as 16, each of which corresponds with one of the ports 10, and a valve box 13 applied to the washer stand-pipe and to the 35 heat flue, the valve box communicating with the washer stand-pipe and heat flue, according to the position of a controlling valve 17 which is mounted to reciprocate in the valve box 13 with relation to the ports 10 and 16 in order that they may be opened or closed at the will of an operator. Any suitable joint or slideway may be provided between the valve and the valve box to insure proper sealing of the ports, but those are details of 40 construction which may be changed to suit particular requirements.

45 As one embodiment of a means for holding the valve slidably seated, retaining strips 18 may be secured in any appropriate way to the inner wall of the valve box, and the valve may have flanges or reduced edges 19 which are slidable between the surfaces of the washer stand-pipe and heat flue, being retained in such relation by the strips 18. Of course an airtight joint will preferably be formed between the valve box 13 and the pipe 14 which connects the valve box with a retort.

50 As a means for manipulating the valve in the box, each valve box may have a rod 20 which is connected to the valve and which has its outer end connected to a lever 21 pivoted on an arm 22, which lever may be manipulated to move the valve so that it will 55 close a port 10 or a port 16. It will be desir-

able also to provide the valve box with an opening of suitable type, through which the link or rod 20 is passed and will move to provide means for rendering the opening leak-proof between the valve box and the said rod.

70 It will be apparent from an inspection of the drawing and from the foregoing description that any deposits which accumulate in the connections between the washer stand-pipe and the mouth pieces 13 and 14 while the retort is being used for the manufacture or 75 production of gas can be subjected to the radiating heat from the retort while the retort is being recharged. When an operator sets the valves to establish communication between the stand-pipe and the retort, communication between the retort and the heat flue will be interrupted, whereas when the valve is set to interrupt communication between the stand-pipe and the retort, hot gas 80 from the retort will pass to the waste heat flue through the valve boxes, so that the said valve boxes and their communications will be used for the purpose of removing deposits which would tend to foul the stand-pipe and 85 the retorts. By reason of the provision of the alternate connections between the retort, the stand-pipe and the heat flue, the connections will be utilized to remove burned out products approximately every four or six hours, 90 which is the charging time in most plants. Owing to the fact that the deposits are frequently burned out or removed, the deposits will be very small during each run and hence the deposits will be more readily removed 95 when a draft through the retort is directed into the valve box in the manner stated.

100 The interior of the washer stand-pipe is provided with a deflector 23 at each of the ports to prevent water from running into the valve box and gaining access to the mouth piece of a retort.

I claim:

110 1. In a gas producing apparatus, the combination with a retort having a mouth piece, two substantially parallel flues adjacent to each other, one of the flues constituting a stand-pipe and the other flue a waste heat flue, an opening into each of these flues, a 115 casing which overlies the openings and communicates with the mouth piece, and a cut-off movable in the casing so as to close either of the openings alternately and allow the other to remain open simultaneously.

120 2. In a gas producing apparatus, the combination with a retort having a mouth piece, two substantially parallel flues adjacent to each other, one of the flues constituting a stand-pipe and the other flue a waste heat 125 flue, an opening into each of these flues, a casing which overlies the openings and communicates with the mouth piece, and a cut-off slidably movable in the casing so as to close either of the openings alternately and 130

allow the other to remain open simultaneously.

3. In a gas producing apparatus, the combination with a retort having a mouth piece, two substantially parallel flues adjacent to each other, one of the flues constituting a stand-pipe and the other flue a waste heat flue, an opening into each of these flues, a casing which overlies the openings and communicates with the mouth piece, a cut-off movable in the casing so as to close either of the openings alternately and allow the other to remain open simultaneously, and a deflector within the stand-pipe above and adjacent to the opening thereinto.
